UNITED STATES PATENT OFFICE

HENRY W. PETERS, OF BOSTON, MASSACHUSETTS, ASSIGNOR TO H. W. PETERS CO. INC.,
OF BOSTON, MASSACHUSETTS

ARTICLE OF JEWELRY

Application filed January 7, 1929. Serial No. 330,904.

This invention relates to articles of jewelry such as finger rings, bracelets, scarf pins, etc., the primary object being to provide simple and efficient means whereby stones and other settings may be held securely in the bezels so that they cannot be removed without mutilating the article. 5

A further object is to provide fastening means made integral with the ring or other article of jewelry, the same being invisible while the setting is in position.

With the foregoing and other objects in view which will appear as the description proceeds, the invention resides in the combination and arrangement of parts and in the details of construction hereinafter described and claimed, it being understood that changes in the precise embodiment of the invention herein disclosed may be made 20 within the scope of what is claimed without departing from the spirit of the invention.

In the accompanying drawings the preferred forms of the invention have been shown.

23 In said drawings,

Figure 1 is a face view of a finger ring embodying the present improvements.

Figure 2 is a plan view thereof.

Figure 3 is a perspective view of the stone setting used with the ring.

Figure 4 is a section on line 4—4, Figure 2.

Figure 5 is a section through a portion of the ring showing the relative positions of 35 the parts before the setting has been secured in place.

Figure 6 is a section through a portion of a ring having a modified means for holding the setting in position, a portion of the metal of the ring being shown by broken lines in the position in which it is formed before the metal is displaced to hold the setting to the ring.

45 Figure 7 is a side elevation of the ring showing a modified arrangement.

Figure 8 is a perspective view of the setting used with the ring shown in Figure 7.

Figure 9 is a plan view of a portion of a 50 bracelet in which the stones or other set-

tings are assembled by means of another modification of the invention.

Figure 10 is a section on line 10—10, Figure 9.

Referring to the figures by characters of reference, 1 designates the hoop or band of a finger ring provided with a bezel 2 in the form of a box into which a stone or other setting 4 of any desired contour is adapted to be inserted. This setting can be inserted 60 downwardly into the bezel or can be inserted laterally. In any case portions of two opposed faces of the bezel must be in contact with the adjacent opposed sides of the setting 4. In these opposed faces of the setting 4 are formed one or more recesses 5. In the structure illustrated in Figures 1 to 5 inclusive, the setting 4 after being inserted into the recess provided therefor is held in place by using a punch or other suitable implement 70 for forcing metal inwardly from the outer faces of the bezel 2 so as to produce inwardly extending nodes 6 that will enter the recesses 5 and thus prevent the setting 4 from being withdrawn from its seat. The end of the 75 punch or other tool used for this purpose can be so designed that, when the metal is pressed inwardly thereby, an ornamental depression will be left on the outer surface. This depression has been indicated at 7. If preferred, however, and as shown in Figure 6, the bezel, when originally produced, can be formed with outwardly extending nodes 8 at points where the metal is to be displaced inwardly. Thus, after the setting 9 has been 85 inserted into the recess 10 provided therefor in the bezel, this outwardly projecting portion of the metal can be punched inwardly to form a node 11 which will enter the recess 12 provided in the side of the setting. This 90 action will result in flattening or substantially flattening the outer surface of the bezel and by dressing down the same all evidence of the displacement of metal can be eliminated.

Instead of providing a single recess in each of two sides of a setting, two or more recesses such as indicated at 13 may be formed in the setting 14 as shown in Figure 8. Where this arrangement is provided the metal must, of 100

course, be displaced opposite each of the depressions as indicated for example at 15 in Figure 7. This displacement can result in the formation of ornamental depressions or protuberances or it can result in the flattening out of nodes formed on the outer surface of the bezel as shown for example in Figure 6 and already explained.

Another means whereby the setting can be held in the recess provided therefor has been illustrated in Figures 9 and 10. In this modified structure the bezel 16, which constitutes a link of a bracelet, has a seat 17 into which a stone 18 or other setting can be slid laterally. In the bottom of the setting 18 may be formed one or more depressions or recesses 19 and after the setting has been brought to proper position, a portion of the metal forming the bottom of the bezel can be punched or displaced inwardly to produce a node 20 which will extend into the depression 19 and thus hold the setting against withdrawal. While this modified form of the invention has been shown applied to a bracelet it is to be understood that it can also be used in connection with finger rings. All of the means disclosed for holding the settings in place can be utilized in different kinds of jewelry other than those illustrated.

32. What is claimed is:

1. An article of jewelry including a box having two open faces and flat inner walls free from depressions, a setting insertible into the box through one open face for exposure of its outer surface through the other open face and for snug engagement with the flat inner surfaces of the box, said setting having a recess in one edge opening through one surface of the setting, that portion of the surface containing the recess being concealed by the box, and means integral with the box for displacement inwardly into engagement with the cut-away portion of the setting, thereby to hold the setting against withdrawal from the box.

2. An article of jewelry including a box having two open faces and flat inner walls free from depressions, a relatively thin setting insertible into the box through one open face for exposing a surface of the setting through the other open face, there being a depression in one edge of the setting opening through a surface of the setting but concealed by the box, and means integral with the box for displacement inwardly into the depression in the setting to hold the setting against withdrawal from the box.

In testimony that I claim the foregoing as my own, I have hereto affixed my signature.

HENRY W. PETERS.
